UNITED STATES PATENT OFFICE

164,710

GARMENT HANGER

Kathleen A. Perry, Lucan, Ontario, Canada

Application May 9, 1950, Serial No. 9,821

Term of patent 14 years

(Cl. D80—8)

To all whom it may concern:

Be it known that I, Kathleen A. Perry, a citizen of the Dominion of Canada and resident of Lucan, in the Province of Ontario, Dominion of Canada, whose post-office address is Lucan, Ontario, have invented a new, original, and ornamental Design for a Garment Hanger, of which the following is a specification, reference being had to the accompanying drawing, forming part thereof.

The side of the hanger opposite the side shown in Fig. 1 is identical in appearance.

I claim:

The ornamental design for a garment hanger, as shown and described.

KATHLEEN A. PERRY.
